DESIGN FOR A HOLDER FOR BADGE, PENCILS, AND THE LIKE

William A. Sherbondy, Atlanta, Ga.

Application August 19, 1943, Serial No. 110,951

Term of patent 3½ years

(CL. D29—2)

To all whom it may concern:

Be it known that I, William A. Sherbondy, a citizen of the United States and a resident of Atlanta, Fulton County, Georgia, have invented a new, original, and ornamental Design for a Holder for Badge, Pencils, and the like, of which the following is a specification, reference being had to the accompanying drawing, forming part thereof.

Fig. 1 is a front elevational view of a holder for badge, pencils, and the like showing my design.

Fig. 2 is a side elevational view thereof.

Fig. 3 is a top plan view thereof.

Fig. 4 is a bottom plan view thereof.

Fig. 5 is a rear elevational view thereof on a reduced scale.

I claim:

The ornamental design for a holder for badge, pencils, and the like, as shown.

WILLIAM A. SHERBONDY.
